INVENTOR

PETER G. MACGREGOR

BY

Lewis J. Doolittle

ATTORNEY

UNITED STATES PATENT OFFICE.

PETER GRAHAM MACGREGOR, OF PEQUANNOCK, NEW JERSEY, ASSIGNOR TO PYRENE MANUFACTURING COMPANY, A CORPORATION OF DELAWARE.

OUTLET GUARD FOR LIQUID RECEPTACLES.

Original application filed May 11, 1920, Serial No. 380,473. Divided and this application filed April 17, 1922. Serial No. 554,140.

To all whom it may concern:

Be it known that I, PETER G. MACGREGOR, a citizen of the United States, and resident of Pequannock, in the county of Morris and 5 State of New Jersey, have invented certain new and useful Improvements in Outlet Guards for Liquid Receptacles, of which the following is a specification.

This invention relates to a construction 10 and arrangement of a guard for the outlet of a liquid receptacle, such as a fire extinguisher of the type in which an acid is held in a container positioned in the upper part of the receptacle and arranged so that when 15 it is desired to operate the extinguisher the receptacle is inverted, allowing the acid to mix with a salt solution in the receptacle and cause a gas to be generated, creating a pressure which expels the contents of the 20 receptacle.

One of the difficulties met with in the use of ordinary devices of this kind is that when carried on railroad cars, etc., where they are subjected to a constant jarring 25 movement, the ingredients slop over and the solution escapes through the outlet, due to the slopping movement.

This application is a division of my application filed May 11, 1920, under Serial 30 No. 380,473, for fire extinguishers, which application is directed more particularly to the construction and arrangement of the acid container and stopper for use in a fire extinguisher of this type. This application 35 is directed to the novel features of construction and arrangement of the device for preventing the escape, due to the slopping of the liquid, from the receptacle through the outlet.

40 The novel construction and arrangement of the guard, as herein shown and described as adapted for use in connection with a fire extinguisher of the type described, prevents the escape of the liquid, 45 due to the slopping action, when the extinguisher is in its upright or normal inoperative position but permits the discharge of the same when the extinguisher is inverted, to operate the same, through the 50 outlet from the receptacle.

In the drawings I have illustrated one embodiment of the invention applied to an extinguisher of the type indicated. In these drawings, Fig. 1 is an elevation, partly in

section, showing the extinguisher with the 55 guard positioned over the outlet. Figs. 2, 3 and 4 are detail views of the outlet guard.

The receptacle, which contains the liquid solution, is shown at 1 and is provided with a removable cap or cover 2, which also 60 forms a handle for the device, and with an outlet 3 to which a hose 4 and nozzle are attached. All of these parts are of the usual construction and need not be described in detail.

To prevent the solution from entering the outlet 3 and hose 4 when the extinguisher is in the upright position, as shown in Fig. 1, and is subjected to a slopping action, as on railway cars, etc., a guard 5 is attached to the inside of the receptacle 1 over the outlet opening (see Fig. 2). This guard is preferably of circular shape and constructed of a thin piece of perforated metal 70 and may be attached to the receptacle 1 by soldering or other suitable means. A second guard or shield 6, similar in shape to the guard 5, except that it is not perforated and its upper edge is cut off, as indicated at 75 7, Fig. 3, is attached to the wall of the receptacle 1 by a hinge 8 and spring clips 9 and 10 over and adjacent but spaced from the guard 5 and spaced a short distance from the wall of the receptacle 1 to provide an opening for the solution to pass through 80 to the outlet 3 when the device is inverted. This construction is shown in the sectional view, Fig. 2, and in Fig. 3, which is a face view of the guard 6 and its mounting, Fig. 4 being a section of one of the spring clips, 85 taken on the line 4—4 of Fig. 3.

The cut-off portion of the guard 6, at its upper edge, as indicated at 7, provides a space for inserting a finger to raise or open the guard 6 about its hinge 8 to permit access to the perforated guard 5, for cleaning, etc. The hinge construction prevents the guard 6 from dropping into the receptacle 1 when opened.

90 The curved construction of the guards presents a convex face which renders the same more efficient and effective in throwing off the liquid slopped against the same. The combination of the perforated inner guard 5 and the non-perforated outer guard 95 or shield 6, arranged as described and shown, has been found to be very effective in actual tests.

What I claim is:—

1. In a device of the class described, in combination with a receptacle having an outlet, means for preventing the contents of said receptacle from entering said outlet when subjected to a slopping action, said means comprising a perforated guard fixed in position over said outlet and a second guard positioned over and adjacent but spaced from said first guard and hinged at one side to permit the same being opened to provide access to said first guard.

2. In a device of the class described, in combination with a receptacle having an outlet, means for preventing the contents of said receptacle from entering said outlet when subjected to a slopping action, said means comprising a perforated guard fixed in position over said outlet, a second guard positioned over and adjacent but spaced from said first guard and hinged at one side to provide access to said first guard, said guards being curved in form presenting parallel convex inwardly extending surfaces adapted to throw off the liquid when slopped against the same and adapted to permit the passage of the contents of said

receptacle to said outlet when said device is inverted in position.

3. In a device of the class described, in combination with a receptacle having an outlet, a perforated guard positioned over said outlet, a second guard positioned over and adjacent but spaced from said first named guard and also spaced a short distance from the wall of the receptacle, permitting passage of the contents of said receptacle when inverted but preventing the same from passing to the outlet when subjected to a slopping action.

4. A device of the class described and for the purpose specified, comprising a pair of guards curved in form and positioned one over the other, one being fixed in position and perforated and the other spaced therefrom and hinged in position thereover and non-perforated and presenting a convex surface extending inwardly preventing the slopping liquid from entering the outlet over which the guards are positioned.

Signed at Newark, in the county of Essex and State of New Jersey, this 15th day of April, A. D. 1922.

PETER GRAHAM MACGREGOR.
